UNITED STATES PATENT OFFICE.

LLOYD I. WILMANS, OF IRVING, TEXAS.

LINE-TYPE-CASTING MACHINE.

1,238,972.

Specification of Letters Patent. Patented Sept. 4, 1917.

Application filed January 30, 1917. Serial No. 145,389.

To all whom it may concern:

Be it known that I, LLOYD I. WILMANS, a citizen of the United States, residing at Irving, in the county of Dallas and State of Texas, have invented certain new and useful Improvements in Line-Type-Casting Machines, of which the following is a specification.

This invention relates to machines of the kind commonly called linotype machines which cast lines of type on slugs or bars formed in molds from metal supplied by a melting pot. It is important that the level of the molten metal in the melting pot be kept substantially constant in order that a uniform temperature may be maintained and a substantially uniform product produced.

It has long been the practice to supply a melting pot with metal by dropping slugs by hand into the pot after they have been used and various devices have been suggested for automatically feeding or delivering slugs, ingots or billets of metal to the melting pot as often as needed to maintain the level of molten metal therein. My invention relates to machines of this class and my object is to provide novel and efficient means for holding the used or worn out slugs in position to be fed to a melting pot, improved devices for automatically feeding one or more slugs to the pot as often as necessary, and novel and efficient means for sounding an alarm when the supply of slugs in the magazine is exhausted or materially reduced.

The manner in which I accomplish the purposes of my invention will be hereinafter described.

In the accompanying drawings I have shown my improvements applied to a well known form of line-type casting machine, but it will be understood that my invention may be embodied in what are known as inter-type machines and also in other machines of the same general kind in which slugs or bars are cast from metal supplied by a melting pot forming part of the machine.

Figure 1 is a view partly in elevation and partly in section of part of a line casting machine to which my improved devices for automatically feeding metal to the melting pot are applied.

Fig. 2 is a detail view in section illustrating particularly the devices employed for sounding an alarm when the supply of

slugs in the magazine is exhausted or reduced to such an extent as to demand refilling of the magazine.

Fig. 3 is a rear elevation of the mechanism shown in Fig. 1 with parts broken away for the purpose of illustrating more clearly parts of the mechanism otherwise hidden.

Fig. 4 is a top plan view of the mechanism shown in Figs. 1 and 3, the housing or casing shown in Fig. 1 and the slugs magazine being in section.

Fig. 5 is a detail view in perspective showing part of the lower portion of the slugs magazine.

Fig. 6 is a perspective view of the toothed ejector for moving slugs from the magazine and causing them to drop into the melting pot.

Fig. 7 is a perspective view of a dog which, when mounted on a reciprocating carriage, engages the ejector shown in Fig. 6.

Fig. 8 is a perspective view of a portion of the reciprocating carriage forming part of the ejector mechanism.

The remaining figures of the drawings are for the most part on an enlarged scale.

Fig. 9 illustrates in detail and mainly in section the devices for ejecting slugs from the magazine. It also shows part of the mechanism for sounding an alarm at the proper time.

In Fig. 9 the level of the molten metal is shown below that required and the mechanism is in condition to operate.

Fig. 10 is a view similar to Fig. 9 and shows how the mechanism is actuated to remove slugs from the magazine and to deliver them to the melting pot.

Figs. 11 and 12 are similar to Figs. 9 and 10, but in this case the level of the molten metal is sufficiently high and the feed mechanism is automatically adjusted to suspend the feeding of slugs to the melting pot.

In Fig. 11 the ejecting mechanism is in its withdrawn position while in Fig. 12 the mechanism has advanced but without removing any slugs from the magazine.

Figs. 13 and 14 are perspective views on an enlarged scale illustrating details of construction of the slugs magazine.

Fig. 13 shows the lower portion of the magazine in vertical position.

Fig. 14 shows the front section of the magazine in vertical position while the rear section is shown in a horizontal position.

Fig. 15 is a detail view of one of the

brackets employed for connecting the front section of the slugs magazine with its supporting bar.

Fig. 16 is a perspective view of one of the 5 brackets for connecting the rear section of the slugs magazine with the bracket shown in Fig. 15 and which is secured to the front section of the magazine.

In Figs. 17 and 18 I have shown a modified 10 way of ejecting or feeding slugs from the magazine to the melting pot.

In Fig. 17 the liquid level is such that the mechanism is in condition to feed slugs from the magazine when the ejector is advanced.

15 Figs. 18 and 19 are perspective views of parts of the mechanism shown in Fig. 17.

The drawings show a portion only of a line or slug casting machine. The melting pot is indicated at A and a portion of the 20 machine frame is illustrated at B. The driving shaft B' carries a spur wheel b meshing with a similar wheel b' on a shaft b² carrying a pinion b³ meshing with the spur wheel b⁴, which in turn drives a spur wheel 25 b⁵. The shaft B' is supported in brackets b⁶ of the main frame while the shafts of the wheels b', b³, b⁴ and b⁵ are supported in a housing B² which rests on the frame B of the casting machine. The housing B² is provided 30 with devices b⁷, by means of which it may be detachably connected with the machine frame B, which support said housing, and, as shown in Fig. 3, the housing is provided 35 with an intermediate plate b⁸ which serves to support parts of the mechanism.

The mechanism is preferably so timed that with each complete casting operation the spur wheel b will revolve twice and the gearing is preferably such that the wheel b⁵ will 40 revolve once to each two revolutions of the wheel b. The spur wheel b⁵, as shown in Fig. 4, is mounted on a stud shaft attached to the intermediate plate b⁸ and said spur wheel b⁵ is directly connected with the mechanism 45 for operating the ejecting mechanism in the manner hereinafter described.

The magazine D is adapted to hold used or worn-out slugs placed one upon the other and arranged in a vertical stack or pile in 50 such manner that they may be easily ejected and delivered to the melting pot. While some of my improvements are adapted to be used in connection with ingots, billets or other pieces of metal, I prefer to use worn-out slugs for supplying the melting pot, and the magazine which I have invented is especially designed for such slugs. I will 55 hereinafter describe my invention as adapted for use with metal of this kind but where 60 parts of the mechanism hereinafter claimed are adapted for use in connection with other kinds of metal it will be understood that my invention contemplates such use when possible.

65 The magazine, which when filled is ar-

ranged vertically, is made in two parts so connected as to stand together in the manner indicated in Figs. 1 and 13, or to be supported in the manner indicated in Fig. 14. The two sections of the magazine are 70 also so connected that they may be moved from a vertical to a horizontal position together for the purpose hereinafter described. The front section of the magazine comprises a front plate d attached at each end 75 to a vertical bar d' and the rear section comprises a plate d² attached to the vertical bars d³. The plate d² is bent at its lower end and continued forward to form a bottom for the magazine. This bottom is 80 slotted as shown in Fig. 5 and these bottom slots join vertical slots d⁵ in the rear plate of the magazine. The front plate d of the front section does not extend to the bottom of the magazine but terminates at the point indicated at d⁶. Below this point there is a gate d⁷ which is hinged to the plate d at d⁸ and is normally closed by a spring d⁹. The purpose of this spring-pressed gate is to prevent breakage of the magazine walls or 85 other parts of the mechanism should the slugs so adhere to each other as to resist the ejecting operation. This will be made more clear hereinafter. It will be observed that the lower edge of the gate terminates above 90 the bottom of the plate d² leaving a front opening a through which the slugs pass while being ejected. A plate a' arranged below the front opening a at one end of the magazine (see Fig. 4) retards the descent 95 of the slugs at one end after being ejected from the magazine thus causing the slugs to descend endwise into the melting pot. An apron a² guides the slugs while dropping into the pot and also serves as a shield for 100 the thermostatic mechanism hereinafter described.

The front section of the magazine is supported on a bar E arranged horizontally within the housing B². A bracket e is attached to the front section of the magazine on each side and each of these brackets extends rearwardly and is provided with an open bearing e' which rests on the shaft E (Fig. 13). The rear section of the magazine carries on each side of its lower end a bracket F of the kind shown in Fig. 16, and this bracket is formed with an open bearing f which engages a boss or circular flange f' on the bracket e, as clearly shown in Figs. 110 13 and 14.

When the two sections of the magazine are in the position shown in Fig. 1 they 115 serve as holders and guides for the vertical pile of slugs X. When the supply of slugs 120 is exhausted and it is necessary to replenish the magazine the rear section thereof may by means of a handle D' be moved rearwardly and turned to a horizontal position 125 and made to rest on the top of the housing 130

B² in the manner indicated in Fig. 14 without moving the front section of the magazine. After the rear section has been supplied with slugs it may be turned back to the vertical position shown. If it is desired to remove the magazine bodily from the machine this can easily be done. It will be observed that the brackets e and F have open bearings e' and f and that these bearings fit over flat portions e² of the shaft E and the arrangement is such that both sections of the magazine may be turned over to a horizontal position on top of the housing B², at which time the openings in the bearings of the brackets will register with the flat portions e² of the shaft E, and the magazine can be readily detached from the shaft and then carried away.

When the magazine is in a vertical position it is supported on blocks g on the housing to which a cross bar G is attached. The shaft E also supports parts of the mechanism for sounding an alarm when the supply of slugs is reduced or exhausted.

It will be observed by reference particularly to Fig. 2 that fingers h project into the magazine through slotted openings in the rear plate of the magazine and that these fingers form part of an alarm-operating device comprising also a semi-cylindrical casting H provided with a rearwardly projecting arm h'. The casting H embraces the lower portion of the shaft E and a cap h² is applied to the upper portion of the shaft E and is connected with the casting H. The arrangement is such that the alarm-operating device may be readily applied to or detached from the shaft E and it is free to rock on the shaft which latter is always stationary. The rearwardly projecting arm h' is adapted to operate devices for sounding an alarm, which devices will be hereinafter described.

The ejector for delivering slugs from the magazine comprises a bar M (Fig. 6) carrying a series of teeth m adapted to pass through the slots d⁵ in the rear plate of the magazine. The ejector is mounted on a carriage N (Fig. 8) which is provided with side rails n sliding in guides n' carried by the housing B². The carriage is reciprocated by a rod O pivotally connected at one end to lugs n² on the carriage and at its opposite ends pivotally connected to a wrist pin o carried by the spur wheel b⁵. As the wheel b⁵ is continuously rotated the carriage is continuously reciprocated. The ejector shaft M is adapted to rock freely in the carriage but it is provided with a downwardly extending arm m' to which is connected a spring m² which tends to hold the shaft in such position as to hold the teeth m in the vertical position illustrated in Fig. 1 and also in Figs. 9 and 10. The lower rear end of the spring m² is attached

to a bent bar or bracket P, the upper forward end of which serves as a stop for the arm m' which projects downwardly from the ejector. While the teeth m are normally held in the elevated position shown in Fig. 1 by the spring m², they will not retain the position if they encounter an obstruction of sufficient resistance unless some means is provided for holding the rock shaft against a turning movement. The carriage N carries a dog R which is pivoted to lugs n³ projecting forwardly from the carriage and said dog is provided with teeth r which engage in recesses or teeth r' in the rock shaft M. The dog R unless held in an elevated position by some means rests with its teeth r in the recesses r', and when this is the case, as indicated in Figs. 9 and 10, during the reciprocation of the carriage N the rock shaft with its teeth will be carried forward in the manner indicated in Fig. 10 and eject the desired number of slugs, the rock shaft being prevented from a backward turning movement by means of the dog R. The sole function of this dog is to prevent the backward turning of the rock shaft. It does not serve to give a positive turning movement to the rock shaft or to the teeth which it carries. If, however, the dog is held in the position shown in Fig. 11, and the carriage is moved forward, the front edges of the teeth m will strike against the rear edges of the slugs but as these slugs carry a considerable weight it is not possible for the teeth to eject the lower slugs, but these teeth with the rock shaft turn in the manner indicated in Fig. 12, putting the spring m² under tension but not dislodging the slugs from the magazine, the spring of course being so adjusted as to allow the rock shaft to turn, when not engaged by the dog, and to return the rock shaft to its normal position during the retreat of the carriage.

In order to control the operation of the ejector I preferably employ thermostatic devices of the kind shown, that is to say, a device operated by the temperature of the molten metal. This device is preferably so arranged that when it is not in contact or close to the molten metal, as illustrated in Fig. 1 and also in Figs. 9 and 10, the ejecting mechanism will operate to feed metal to the melting pot, but when the device comes in contact with or approaches very close to the surface of the metal in the melting pot, as indicated in Figs. 11 and 12, the device will be operated to suspend the feeding of slugs from the magazine to the pot. The details of construction of such a device may be varied, but preferably it is constructed as follows:

A bulb Q, containing mercury or other suitable fluid, is adjustably connected at q with a tube q', also containing an expandible

and contractible fluid. The tube q' is adjustably connected at its upper end with a plate q^2 , this connection being made secure by a lock nut q^3 . The plate q^2 is attached 5 by screws q^4 to the cross bar G, and between the plate and the cross bar is interposed a flexible diaphragm q^6 . The cross bar G is formed with a recess or opening q^7 above the end of the tube q' , and in this recess or opening is arranged a block S which bears on the diaphragm q^6 . The arrangement is such that as the mercury or other fluid is expanded or contracted the diaphragm is raised and lowered and correspondingly raises and lowers the block or plug S.

A lever T is pivotally connected with a bracket t and carries an arm, preferably a spring arm t' , which bears against a lug r^2 projecting downwardly from the dog R. It 20 is obvious that by the devices shown the dog R may be raised and lowered to the proper extent and at the proper times. Further description of this part of the mechanism seems unnecessary further than to say that in 25 Figs. 9 and 10 the position of the mechanism is shown when it is adjusted automatically to feed slugs to the melting pot. At this time the liquid level is low, as indicated in Figs. 9 and 10, and additional supplies of 30 metal are required. In Figs. 11 and 12 the mercury bulb is shown as being in contact with the metal, and at this time no additional supply of metal is required. The slug ejecting mechanism is thrown out of operation 35 in the manner clearly indicated in Figs. 11 and 12.

In order to sound an alarm when the supply of slugs in the magazine is exhausted, or so much reduced as to be nearly exhausted, 40 I provide the devices before referred to and shown best in Fig. 2. It will be understood that the fingers h normally extend under the pile of slugs in the manner indicated in Fig. 1 and the weight of the slugs holds the fingers down. When, however, this weight is 45 greatly reduced, by reason of the supply of slugs running out, the fingers will rise in the manner indicated in Fig. 2. This is due to the fact that the rear portion h' , h^2 of the 50 device is heavier than the front portion and therefore when the fingers rise the arm h' will be lowered into the path of a cam u on the top of a vertical shaft U, carrying at its lower end a spring arm u' provided with a 55 hammer u^2 adapted to sound a bell u^3 . The shaft U extends through a lug or bracket n^4 on the carriage and moves back and forth therewith. A spring u^5 permits the shaft U to turn about its vertical axis but returns 60 such shaft to its normal position when the cam u is released. In other words the operation is as follows: When the fingers h are elevated and the carriage retreats, the arm h' strikes the cam u and turns the shaft U 65 about its vertical axis. As the carriage fur-

ther moves the cam is released from the arm h' and the shaft U is quickly turned back to its original position by the spring u^5 , in this way sounding the alarm. The alarm will be sounded during each reciprocation of the 70 carriage until the machine is stopped or until the fingers h are lowered either by the introduction of slugs in the magazine or by some other means.

It will be understood that the magazine 75 can be easily replenished in the manner before described and it will also be understood that the thermostatic devices may be accurately adjusted to operate in the proper way to feed slugs to the magazine only when required. Whether or not the ejector shall effect the feeding of the slugs depends upon the temperature to which the bulb Q is subjected. This temperature will vary according to whether the bulb is immersed in the molten metal or whether it is placed close to or far from the surface of the metal. The thermostatic devices which I employ are provided with the means of adjustment hereinbefore referred to which enables me to determine very accurately how the device should be adjusted to feed to melting pots under different conditions or circumstances.

In Figs. 17 and 18 I have shown a somewhat modified or simplified construction. I 95 prefer to use the thermostatic devices heretofore described, and these devices are similarly lettered in Fig. 17. The devices for sounding an alarm are also in general similar to those before described and are similarly lettered. In this case, however, the carriage which supports the ejector is of somewhat different construction. The carriage W is formed integrally with a series of teeth w which are adapted to reciprocate 100 in the slots in the lower portion of the slugs magazine. The carriage itself is adapted to slide in the guideways w' in the side frames of the housing B^2 and said carriage is reciprocated by means of a rod V eccentrically 105 pivoted to the spur wheel b^5 heretofore mentioned. The front end of this rod is not pivotally connected with the carriage as before but is provided with a downwardly extending lug v which projects through a slot 110 w^2 in the carriage and is adapted to move back and forth therein. At the front of the rod V is a head V' having a portion v' which is adapted to engage with lugs v^2 , integral with or firmly secured to the carriage W 115 and arranged on opposite sides of the slot w^2 . When the rod V is in its lowermost position, as indicated in Fig. 17, the portion v' of the head V' will engage the lugs v^2 and the carriage will be reciprocated and 120 will effect the ejection of slugs from the magazine, but if the front portion or head of the rod V is raised so that the front portion of the head occupies a plane above the top of the lugs v^2 then the rod will recipro- 125 130

cate without reciprocating the carriage and hence the ejecting teeth will not operate upon the slugs. The manner in which the rod V is raised and lowered is clearly indicated. When the level of the molten metal is low the rod V is in its lowermost position and the carriage with the ejecting teeth will be properly operated, but as soon as the level in the melting pot rises the arm T, with its 10 spring finger t', will be raised in such manner as to raise the head V' above the lugs v², and hence the carriage will remain stationary until the fluid level in the melting pot falls.

15 The magazine illustrated in Fig. 17 may be of the same construction as that hereinbefore described and unless otherwise indicated the mechanism used in connection with the devices illustrated in Figs. 17, 18 and 19 20 is the same in all respects as that shown in the preceding figures of the drawings and hereinbefore described. While I prefer to employ the form of thermostat illustrated for operating the lever t, which controls the 25 operation of the ejector, it is obvious that other devices might be employed for operating said lever.

I claim as my invention:

1. The combination with the melting pot 30 of a line-type casting machine, of means for supplying metal thereto when required comprising a magazine, devices for ejecting metal from the magazine, and thermostatically controlled mechanism for actuating said ejecting devices.

2. The combination with the melting pot of a line-type casting machine, of a magazine 40 for holding metal slugs, an ejector for discharging slugs from the bottom of said magazine, means for actuating said ejector, and thermostatically operated devices for controlling the operation of the ejector actuating mechanism.

3. The combination with the melting pot 45 of a line-type casting machine, of a magazine for holding slugs of metal, a toothed ejector for discharging slugs from the magazine, and thermostatically controlled devices for suspending the operation of the ejector.

50 4. The combination with the melting pot of a line-type casting machine, of a magazine for holding slugs of metal to be supplied to the melting pot, a reciprocating carriage, a toothed ejector shaft pivotally mounted in the carriage, means for holding the ejector shaft in normal position, a dog for preventing the ejector shaft from turning, and thermostatically operated devices for controlling the position of the dog.

60 5. The combination with the melting pot of a line-type casting machine, of a magazine for holding slugs of metal to be supplied to the melting pot, a reciprocating carriage, a toothed ejector shaft pivotally mounted in the carriage, means for holding

the shaft in normal position, a dog for preventing the ejector shaft from turning, a pivoted lever engaging the dog for raising and lowering it, and means for automatically operating said lever correspondingly 70 with the rise and fall of the molten metal in the melting pot.

6. The combination with a slugs magazine of an alarm device, and means operated by a decrease of weight of metal in the slugs 75 magazine for actuating said alarm device.

7. The combination with a magazine for holding metal to be supplied to a melting pot, of a finger extending into the lower portion of the magazine and upon which 80 the metal rests, a reciprocating carriage provided with means for ejecting metal from the magazine, and an alarm device supported on the carriage and adapted to be brought into operative connection with said finger when the weight of metal in the magazine is sufficiently diminished.

8. The combination with a magazine for holding metal to be supplied to a melting pot, of a pivotally mounted finger extending into the lower portion of the magazine, 90 an arm connected to said finger and movable coincidently therewith, means for ejecting metal from the magazine, and an alarm device brought into operative relation with 95 said arm when the weight of metal in the magazine is reduced to a predetermined extent.

9. A magazine for holding metal to be supplied to a melting pot made in separable 100 sections one of which sections is adapted to be moved from a vertical to a horizontal position without moving the other section while both sections are adapted to be moved together, and a shaft to which the sections 105 are connected, about which they may be swung together, and from which they may be bodily removed.

10. A magazine for holding metal to be supplied to a melting pot made in two sections 110 one of said sections being provided with rearwardly extending brackets and the other with brackets pivotally connected with the brackets of the front section in combination with a shaft on which the brackets are supported, the arrangement being such that the rear section of the magazine may be moved from a vertical to a horizontal position without moving the front section or both sections may be moved together.

11. A magazine for holding metal to be fed to a melting pot comprising a front section having rearwardly extending brackets and formed with open bearings, a horizontally arranged shaft extending through 115 said open bearings and provided with reduced or flattened portions, and a rear magazine section provided with brackets pivotally connected with the brackets of the front section and which have open 120 125

- bearings through which said horizontally arranged shaft extends the arrangement being such that when the magazine sections are in a vertical position they are inseparably connected with the shaft but when both magazine sections are moved to a horizontal position they can be separated from the shaft and be withdrawn bodily from the machine.
- 10 12. The combination with the melting pot of a line-type casting machine, of means for supplying metal thereto when required comprising a magazine, devices for ejecting metal from the magazine, devices for controlling the operation of the ejecting mechanism including a pivoted lever, and a thermostat provided with means for ad-
- 15

justing it to cause it to be brought into operation at the required temperature or 20 the required level of the metal in the melting pot.

13. The combination with the melting pot of a line-type casting machine, of means for supplying metal thereto when required comprising a magazine, a cross bar beneath the magazine, a thermostat supported by said cross bar, a lever operated by said thermostat, and devices for ejecting metal from the magazine the operation of which is controlled by the thermostatically operated lever.

In testimony whereof, I have hereunto subscribed my name.

LLOYD I. WILMANS.
